CHEMICAL PUMP FOR OIL WELLS

Charles R. Berkley, Odessa, Tex., assignor to Gulf Oil Corporation, Pittsburgh, Pa., a corporation of Pennsylvania

Filed Apr. 10, 1962, Ser. No. 186,406
5 Claims. (Cl. 103—6)

This invention relates to a pump, and more particularly to a pump for injecting liquid chemicals into the flow lines from a well.

Frequently, it is desirable to inject a liquid chemical treating agent into the stream of fluids flowing through the flow line from a well. One or more objectionable conditions in the flow line may be alleviated by the injected chemical. For example, the fluid produced by the well may be corrosive. It is then desirable to inject a corrosion inhibitor into the stream to prevent excessive corrosion of the flow line. In other instances, the well may produce a paraffinic oil which tends to deposit paraffin on the wall of the flow line. It is then desirable to inject into the flow line a fluid which will prevent the accumulation of paraffin deposits on the flow line wall.

A number of different arrangements of pumps in combination with well head structures has been suggested to accomplish the desired object of pumping a liquid into the flow line of a well at a controlled rate. One commonly used arrangement is to provide a separate drive for the chemical pump. Another arrangement uses a mechanical linkage driven by the walking beam of the well pumping unit to drive the chemical pump. Although the apparatus driven by the walking beam has an important advantage in cost over the units having separate drives, it has heretofore not been as readily installed at the well. The well pumping units of different manufacturers vary widely in their design, and even the pumping units of a single manufacturer differ widely in size, depending upon the rate of production of a particular well. Because of the large number of different types and sizes of pumping units and different arrangements of apparatus at the well head, the chemical pumps driven from the walking beam have required a substantial amount of fabrication at the well head.

The many different problems encountered in the flow lines of wells require different chemicals for their solution; hence, there is a wide variation in the properties of chemicals injected into flow lines from different wells. Some of the chemicals are solvents of very low viscosity, while others are highly viscous compositions. Moreover, because of the wide variation in rates of flow through the flow lines of wells as well as the necessity of injecting chemicals at rates designed to produce different concentrations in the flow line liquids, wide latitude in adjustment of the flow rate of the chemical is essential. Particularly when the chemical treating agent is an expensive reagent injected into the flow line at low rates, it is necessary to provide a very fine adjustment of the rate of discharge of the chemicals from the chemical pump as well as an adjustment over a wide range of flow rates.

This invention resides in a novel chemical pump for the injection of liquid chemical treating agents into the flow line of wells through which flows a stream of well fluids produced by a reciprocating pump within the well. In the apparatus of this invention, a striker plate mounted at the well head on the polish rod driving the well pump engages suitable linkage to drive a plunger in the chemical pump downwardly in a pump cylinder to discharge the chemical from the lower end of the pump. After initial installation of the striker plate on the polish rod, the length of stroke of the chemical pump can be regulated by adjustment of the length of the plunger. A metering

2

valve at the inlet of the chemical pump provides further control of the rate of discharge of liquids from the chemical pump.

In the drawings:

5 FIGURE 1 is a diagrammatic view, partially in vertical section, of the pump of this invention assembled in position for operation;

10 FIGURE 2 is a vertical sectional view of the pump showing the plunger structure and mechanism for returning the plunger to an upper position;

15 FIGURE 3 is a vertical sectional view of a metering valve provided at the inlet of the pump; and

20 FIGURE 4 is a diagrammatic view showing a modified embodiment of this invention installed on a flow line 15 of a well.

25 Referring to FIGURE 1, a well indicated generally by reference numeral 10 is illustrated with a polish rod 12 extending upwardly through a packing gland 14 for connection to a walking beam 16 of a pumping unit in accordance with conventional practice. The walking beam is driven by the usual means such as a pitman drive, not shown in the drawings. Extending from the well is a flow line 18 for the delivery of well fluids to suitable storage, not shown.

30 Positioned adjacent the well 10 is a storage tank 20 which is shown resting on a platform around the well. Within the storage tank 20 is a chemical pump, indicated generally by reference numeral 22. The chemical pump 22 is shown with a nipple 24 connecting the inlet port, not shown in FIGURE 1, of the pump with a metering valve 26. Extending upwardly from the metering valve 26 is a metering rod 28 which forms an extension of valve stem 30 of the metering valve. Metering rod 28 is provided with a threaded section 32 near its upper end having a lock nut 34 movable thereon and adapted to engage a plate on the cover 36 of the storage tank 20 to lock the metering rod in position.

35 Connected to the lower end of the pump 22 is a discharge line 38 which is shown extending upwardly through the storage tank 20 and out of the upper end thereon. A pressure gauge 40 may be connected in the discharge line 38 for indication of the pressure developed by the chemical pump. A bleed valve 42 is connected to the side outlet of a T 44 in the discharge line. The discharge line 38 continues past the T 44 and is connected to the well flow line 18. A valve 46 is installed in the discharge line 38 between the T 44 and the flow line 18.

40 Referring to FIGURE 2, the chemical pump 22 has a pump cylinder 48 having a bore 50 extending vertically therethrough intersected by an inlet port 52. Extending upwardly from the pump cylinder 48 is a tubular housing 54 which is internally threaded at its upper end to receive a bushing 56. At the lower end of the pump cylinder 48 is a check valve 58 having a central opening therethrough communicating with the bore 50. Within the check valve body 58 is a ball valve 60 urged upwardly against a valve seat 64 by a compressed helical spring 62. The check valve allows downward flow from the bore 50 into an L 66 which forms part of the discharge line 38.

45 Fitting slidably within the bore 50 of the pump cylinder 48 is a pump plunger 68 which extends upwardly out of the pump cylinder 48 into the housing 54. Leakage around plunger 68 is prevented by an O-ring 69 in a recess in the upper end of the bore 50. An extension tube 70 threaded to the upper end of the pump plunger 68 extends upwardly through the bushing 56. Surrounding the plunger 68 and extension tube 70 within the housing 54 is a helical spring 72 which is compressed 50 between the upper end of the pump cylinder 48 and a collar 75 secured at a desired position on the extension

tubing 70 by means of a set screw 76. A sleeve 74 surrounding extension 70 rests on collar 75. Secured in the upper end of bushing 56 is a stop collar 78 which is adapted to engage the upper end of the sleeve 74 and thereby limit upward movement of the plunger 68. A 5 plunger head 80 threaded to the upper end of the extension tube 70 can be locked in place by a lock nut 82.

Adjustment of the compression of the spring 72 is accomplished by changing the position of collar 75. If a change in the extent of upward movement of the plunger 68 is desired, a sleeve of suitable length is substituted for sleeve 74 to compensate for the change in position of collar 75. In general, the compression of spring 72 and the extent of upward movement of the plunger are greater 10 for chemical liquids of high viscosity.

Referring to FIG. 3, the metering valve 26 is illustrated having a side outlet 84 threaded for connection to the nipple 24. Valve stem 30 extends downwardly through a packing gland 86 and is provided at its lower end with a conical surface 88 adapted to engage a valve seat 90 to provide a needle valve permitting fine control of the rate of flow into the chemical pump. Flow into the metering valve is through an inlet screen 92 connected to an L 94 having an opening therethrough communicating with a vertical passage 96 in the metering valve 25 to the valve seat 90.

As shown in FIGURE 1, on the top of the cover 36 of the storage tank is a pair of brackets 98 with a rotatable shaft 100 extending between them. Secured to the shaft 100 is a lever arm 102 made up of a tubular member connected to the shaft into which an extension 104 is 30 slidable. The position of extension 104 can be adjusted by means of a set screw 106. At the outer end of the extension 104 is a collar 108 threaded to receive a 35 threaded striker pin 110. A lock nut 112 on the striker pin can be tightened against the collar 108 to secure the 40 striker pin in the desired position.

The lever arm 102 extends directly above the plunger head 80 to drive the pump in the manner hereinafter described. For convenience in assembly, the apparatus 45 positioned within the storage tank 20 is assembled on a plate 114, which in turn is secured to the cover 36 of the storage tank. The pump 22 extends upwardly through a nut 116 secured on the plate 114 and is locked at the 50 desired elevation by means of a set screw 120 which engages housing 54.

In the operation of the chemical pump of this invention, the storage tank 20 is set in place, preferably as close as possible to the well head. The head 80 of the pump plunger is moved to an upper position on the plunger and the lever arm pressed downwardly to move the lower end of the pump plunger 68 to the bottom of the bore 50. With the pump plunger held in this lower position, the walking beam 16 is moved to its lowest position to locate the polish rod 12 at its lowest position. A striker plate 122 is then fastened on the polish rod just above the striker pin 110. The striker pin 110 is then 55 raised in collar 108 until it just touches the lower surface of the striker plate 122 and is locked in that position. It is a common practice to rotate the polish rod and sucker rod of a pump during operation of the well pump. For this reason, it is preferred that the striker plate 122 be a circular disc.

The walking beam 16 is then raised to raise the striker plate 122 out of engagement with the striker pin 110. The compressed spring 72 within the housing 54 raises the pump plunger 68 to the uppermost position determined by the sleeve 74. The head 80 of the plunger is then adjusted downwardly to shorten the effective length of the plunger and thereby fix the length of stroke of the pump plunger 68 below the inlet port, which in turn controls the amount of liquid discharged by each stroke of the plunger.

With valve 46 closed and valve 42 open, the well pumping unit is placed in operation. The striker plate 122

engages the striker pin 110 on each stroke of the well pump and moves the lever arm 102 downward. Downward movement of lever arm 102 forces the pump plunger downwardly in the pump to discharge liquid from the bore 50.

The rate of pumping is measured by observation of the rate of discharge through the bleeder valve 42. Major 10 adjustments in the rate of flow are made by adjustment of the effective length of the pump plunger by adjustment of the position of plunger head 80 on plunger extension 70. After the rate of discharge from the pump 22 is close to the desired value, final adjustments are made by means of metering valve 26. Valve 46 is then opened and valve 42 is closed. The metering valve is particularly 15 effective when the chemical to be injected into the flow line of the well is highly viscous. The metering valve also allows accurate adjustment of the rate of flow or complete shut off of the chemical pump to be made while the well pumping unit continues in operation. On the upward movement of the polish rod 12, the striker plate 122 moves out of engagement with striker pin 110. Spring 72 moves the pump plunger upwardly to a position with its lower end above the inlet port 52 in the pump cylinder 48. A weak spring 124 holds the lever arm 20 25 102 against the plunger head.

Referring to FIGURE 4 of the drawings, a modified arrangement is illustrated in which the storage tank 20 is mounted on an adjustable base 126. The base 126 is supported directly on the flow line 18 of the well.

The unique driving mechanism for the chemical pump described herein permits a single pump structure to be utilized with a wide variety of sizes and types of well pumping units. The long vertical span of the polish rod over which the striker plate 122 may be attached provides 30 a maximum flexibility for the installation of the chemical pump assembly. Driving of the chemical pump directly from the polish rod is also advantageous in providing a compact unit immediately adjacent the well head, and thereby greatly decreases the chances of damage to the 35 assembled apparatus. The ease of adaptation of the chemical pump for different types of units allows it to be 40 installed by ordinary oil field workers.

The combination of the metering valve and the plunger of adjustable length provides a wide range of adjustment 45 of the capacity of the pump while permitting very accurate control of the flow rate even when the rate of injection of the chemical into the flow line is extremely low. With this arrangement, a single chemical pump structure can be used for pumping chemicals of widely different characteristics, as well as for pumping the chemicals at widely 50 different rates. The metering valve is also highly effective in permitting accurate adjustment of the pumping rate while the well pumping unit remains in operation. Accurate adjustment of the rate of discharge is facilitated 55 because the change in the position of the plunger head 80 on the plunger extension 70 is the same as the change in the effective stroke of the plunger; hence, the extent of adjustment can be observed directly.

I claim:

1. Apparatus for the injection of a liquid into the flow line of an oil well equipped with a reciprocating pump driven by a polish rod extending upwardly from the well head comprising a storage tank for the liquid, a pump cylinder positioned in said storage tank, said pump cylinder having a bore extending vertically therethrough, an inlet port extending through the cylinder and intersecting the bore above the lower end thereof, conduit means from the lower end of the cylinder to the flow line of the pump for delivery of liquids from the pump into the flow line, 60 a check valve in the conduit means, a plunger movable in the bore of the cylinder from a position above the inlet port to a position below the inlet port, a striker plate mounted on the polish rod, an arm unattached to the striker plate extending to a position below the striker plate whereby said arm is engaged and moved down-

wardly by the striker plate on downward movement of the striker plate, said arm extending over the upper end of the plunger and adapted to move the plunger downwardly on downward movement of the polish rod to its lowermost position to drive the plunger downwardly in the bore of the pump, means for adjusting the length of the plunger to control the distance below the inlet valve traveled by the plunger, and resilient means engaging the plunger to urge said plunger upwardly against the arm.

2. Apparatus for the injection of a liquid into the flow line of an oil well equipped with a reciprocating pump driven by a polish rod extending upwardly from the well head comprising a storage tank, a pump cylinder positioned in said storage tank, said pump cylinder having a bore extending vertically therethrough, an inlet port extending through the cylinder and intersecting the bore above the lower end thereof, a metering valve connected in that port, conduit means from the lower end of the cylinder to the flow line of the well for delivery of liquids from the pump into the flow line, a check valve in the conduit means, a plunger movable in the bore of the cylinder from a position above the inlet port to a position below the inlet port, a striker plate mounted on the polish rod, an arm unattached to the striker plate extending below the striker plate for engagement by the striker plate on downward movement thereof, said arm extending over the plunger and adapted to move the plunger downwardly on downward movement of the polish rod to drive the plunger downwardly in the bore of the pump, means for adjusting the length of the plunger to control the distance below the inlet port traveled by the plunger, and resilient means engaging the plunger to urge said plunger upwardly against the arm and return the plunger to a position above the inlet port.

3. Apparatus for the injection of liquid into the flow line of an oil well equipped with a reciprocating pump driven by a polish rod, comprising a storage tank, a pump cylinder having a bore extending vertically therethrough, an inlet port extending through the cylinder and intersecting the bore above the lower end thereof, conduit means from the lower end of the cylinder to the flow line of the well for delivery of liquids from the pump cylinder into said flow line, a check valve in the conduit means, a plunger movable in the bore of the cylinder between a position above the inlet port and a position below the inlet port, a tubular housing extending upwardly from the pump cylinder, said pump plunger extending upwardly through the housing to a position above the upper end thereof, a sleeve mounted on the pump plunger above the pump cylinder, a helical spring compressed between the pump cylinder and the sleeve to urge the pump plunger upwardly, means extending inwardly from the housing above the sleeve to engage the sleeve and limit upward movement of the plunger, a striker plate mounted on the polish rod, an arm pivotally mounted on the storage tank extending directly above the upper end of the plunger, said arm being unattached to the striker plate and extending to a position below the striker plate whereby downward movement of the plunger to its lowermost position moves the arm against the upper end of the plunger to drive the plunger downwardly, and means for adjusting the length of the plunger to control the distance below the inlet port traveled by the plunger.

movement of the plunger, a striker plate mounted on the polish rod, an arm pivotally mounted on the storage tank extending directly above the upper end of the plunger, said arm being unattached to the striker plate and extending to a position below the striker plate whereby downward movement of the plunger to its lowermost position moves the arm against the upper end of the plunger to drive the plunger downwardly, and means for adjusting the length of the plunger to control the distance below the inlet port traveled by the plunger.

4. Apparatus as set forth in claim 4 in which an inlet line extends from the inlet port for delivery of the liquid to the inlet port, and a metering valve connected in the inlet line.

5. A chemical pump for the injection of liquid into the flow line of an oil well equipped with a reciprocating pump driven by a polish rod connected to a walking beam, comprising a storage tank, a pump cylinder having a bore extending vertically therethrough, an inlet port extending through the cylinder and intersecting the bore above the lower end thereof, conduit means from the lower end of the cylinder to the flow line of the well for delivery of liquids from the pump cylinder into said flow line, a check valve in the conduit means, a plunger movable in the bore of the cylinder between a position above the inlet port and a position below the inlet port, a tubular housing extending upwardly from the pump cylinder, said pump plunger extending upwardly through the housing to a position above the upper end thereof, a sleeve secured on the pump plunger above the pump cylinder, a helical spring compressed between the pump cylinder and the sleeve to urge the pump plunger upwardly, means extending inwardly from the housing above the sleeve to engage the sleeve and limit upward movement of the plunger, a striker plate mounted on the polish rod, an arm pivotally mounted on the storage tank extending directly above the upper end of the plunger, said arm being unattached to the striker plate and extending to a position below the striker plate whereby downward movement of the plunger to its lowermost position moves the arm against the upper end of the plunger to drive the plunger downwardly, and means for adjusting the length of the plunger to control the distance below the inlet port traveled by the plunger.

30 6. Apparatus as set forth in claim 5 in which the helical spring is compressed between the pump cylinder and the sleeve to urge the pump plunger upwardly, means extending inwardly from the housing above the sleeve to engage the sleeve and limit upward movement of the plunger, a striker plate mounted on the polish rod, an arm pivotally mounted on the storage tank extending directly above the upper end of the plunger, said arm being unattached to the striker plate and extending to a position below the striker plate whereby downward movement of the plunger to its lowermost position moves the arm against the upper end of the plunger to drive the plunger downwardly, and means for adjusting the length of the plunger to control the distance below the inlet port traveled by the plunger.
